MOUNTING FOR LOUD SPEAKERS IN
PIANOS

John Hays Hammond, Jr., Gloucester, Mass.

Application December 18, 1929, Serial No. 414,871
Renewed August 31, 1933

9 Claims. (Cl. 179—1)

The invention relates in general to pianos, and more particularly to a piano having a loud speaker associated therewith.

The invention further relates to a piano having a radio receiver associated therewith by which radio programs may be received and heard through the loud speaker. The piano may also include a regenerative arrangement for picking up the vibrations of the strings and sounding board, amplifying them by the radio receiver and delivering the amplified vibrations to the loud speaker, the loud speaker being in regenerative relation to the sounding board and strings. According to the invention arrangement may be made for shifting the position of the loud speaker, with respect to the piano sounding board, to different positions for radio reception and piano regenerative operation.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is a side view of a piano illustrating the invention;

Fig. 2 is an end view with a part section taken on the line 2—2 of Fig. 1;

Fig. 3 is an enlarged side elevation with parts broken away, further illustrating the shifting arrangement for shifting the loud speaker; and

Fig. 4 is a bottom plan view of part of the piano shown in Fig. 3.

In the following description and in the claims parts will be identified by specific names for convenience, but they are intended to be as generic in their application to similar parts as the art will permit.

Like reference characters denote like parts in the several figures of the drawings.

Referring to the drawings more in detail, the invention is shown by way of illustration as applied to a grand piano 10 having strings 11 and a sounding board 12. Loud pedal 13 is employed for controlling the amplitude of vibrations of the strings in a well known manner.

Located at various points on the sounding board 12 are a plurality of pickup devices 14 which are adapted to be actuated by the vibra-

tions of said sounding board and to produce a varying electric current which is applied to transformers 15, the secondaries of which are connected to a plurality of potentiometers 16. Said potentiometers are connected in series to a potentiometer 17, the movable contact 18 of which is mounted on a lever 19 which is actuated from loud pedal 13 by a rod 20. Said rod carries a collar 22 which cooperates with lever 19 for elevating the same when pedal 13 is depressed. Spring 21 may be employed for normally holding lever 19 in its lower position. 5

Radio receiver 25 which may be of any well known type as, for example, one including a radio frequency amplifier 26, a detector section 27, and 15 an audio frequency amplifier 28 may be connected to an antenna 29 through knife switch 30. The output circuit of receiver 25 may be connected to loud speaker 31 by leads 32. 10

The variable contact 18 and one side of potentiometer 17 are connected through switch 23 across the input circuit of detector section 27 whereby the audio frequency currents produced by pickup devices 14 may be applied to said detector element, amplified in audio amplifier 28 25 and used to actuate loud speaker 31. 20

Pickup devices 14 are preferably located at antinodal points on sounding board 12 so that a maximum response will be obtained. Loud speaker 31 is preferably located at a nodal point 30 on said sounding board so that the operation of the sounding board will not be interfered with thereby.

The arrangement for shifting the loud speaker 31 will now be described. The sounding board 35 12 is provided with an opening 114 around which on the lower side is a strip of leather or other suitable material 115. Located below the opening 114 is the loud speaker 31.

Secured to the lower side of the piano is a 40 frame 122 having aligned openings in which is slidably mounted a plunger 121 attached to the frame of loud speaker 31. The plunger 121 has an opening 124 in which is positioned an arm 123 provided with a cam surface 125. The arm 45 123 is pivoted to the frame 122 by pivot 140.

At the front of the piano is an operating lever 127 having a handle 129 and pivoted to the under surface of the piano by a pivot 128. The arm 127 carries a roller 126 which engages the cam surface 125. It will be seen that by moving the handle 129 back and forth the roller 126 will move along cam surface 125 and shift the loud speaker 31 from a lower position, as illustrated, 50 to an upper position with the loud speaker 55.

jammed or clamped against the leather washer 115.

To operate the piano as a radio receiver switch 30 is closed and switch 23 is open. The signals 5 received over antenna 29 pass through the radio amplifier 26, detector 27 and audio amplifier 28 to the loud speaker 31. To operate the system as a regenerative piano switch 30 is opened and switch 23 is closed. Vibrations of strings 11 cause 10 vibrations of sounding board 12 which are picked up by pickup devices 14, passed through the audio amplifier 28 and applied to loud speaker 31. The vibrations from loud speaker 31 are impressed on the sounding board 12 and on the strings 11 15 and are again picked up by the pickup devices 14, amplified by amplifier 28 and again impressed on loud speaker 31, providing a regenerative action.

The operation of the piano both as a radio receiver and as a regenerative piano is described in 20 application, Serial No. 384,284, filed August 8, 1929, to which attention is called for a more complete disclosure of the apparatus and the circuits governing the action thereof.

25 It has been found that a substantial difference in tone is produced by shifting loud speaker 31 from a position against the sounding board 12 to a position spaced therefrom. It has been found that, particularly with a so called dynamic loud 30 speaker, best sound reproduction is obtained when using the system as a regenerative piano, when the loud speaker is moved into a position spaced from the sounding board 12. On the other hand, when the piano is used as a radio receiver best 35 sound reproduction is obtained when the loud speaker 31 is clamped against the sounding board 12.

Although a particular type of loud speaker 31 is 40 disclosed for purposes of illustration, it will be understood that other types of loud speaker may also be used in the present system and in the manner above described. For a more complete drawing and description of the loud speaker used, for 45 purposes of illustration, attention is called to application, Serial No. 370,484, filed June 13, 1929, now Patent No. 1,893,892, granted Jan. 10, 1933.

Thus, an arrangement has been provided for 50 conveniently changing the relative position of a loud speaker with respect to the sounding board 55 of the piano to obtain different sound reproduction. The loud speaker may be in one position when using the piano as a regenerative piano and it may be in the other position when using the piano as a radio receiver as above described. 55 However, it may be desirable to use both positions of the loud speaker to give different effects when both using the piano regeneratively and as a radio receiver.

60 While certain novel features of the invention have been shown and described and are pointed out in the annexed claims, it will be understood that various omissions, substitutions and changes in the forms and details of the device illustrated and in its operation may be made by those skilled 65 in the art without departing from the spirit of the invention.

What is claimed is:

1. The method of operating a piano or the like 70 having a sound board and also having a loud speaker associated therewith which comprises impressing electric variations corresponding to sound variations on said loud speaker and adjust-

ing the distance between the loud speaker as a whole and the sound board to obtain different tone characteristics.

2. In a piano, a piano sounding board having an opening, a loud speaker having a loud speaker frame, a washer of soft material around said opening, an adjustable mounting for said loud speaker whereby said loud speaker frame may be clamped against said washer and may be spaced from said board, selectively. 5

3. In a piano, a piano sounding board, a loud speaker, a broadcast receiver, means for connecting said sounding board with said receiver and loud speaker to cause the piano to regenerate, and means for connecting said receiver and loud speaker to receive a program from sources external to the piano, and means for adjusting the loud speaker with respect to said sounding board 10 to obtain different tone characteristics.

4. In a piano, a piano sounding board, a piano 20 frame supporting said sounding board, a loud speaker having a loud speaker frame, said loud speaker frame having a post attached thereto, said piano frame having a guide slidably seating said post, a member pivoted to said piano frame 25 and to said post, an operating member at the front of the piano and pivoted to the piano frame, one of said members having a cam surface and other member having a follower part engaging said cam surface. 30

5. In a piano, a piano sounding board, a piano frame supporting said sounding board, a loud speaker having a loud speaker frame, said loud speaker frame having a post attached thereto, said piano frame having a guide slidably seating 35 said post, a rod pivoted to said piano frame and to said post and having a cam surface, an operating lever at the front of the piano pivoted to the piano frame and having a part engaging said cam surface. 40

6. In a piano, a sounding board, a loud speaker, means for causing said loud speaker to reproduce a broadcast program or the vibrations of said sounding board and means for clamping said loud speaker to said sounding board or spacing it a 45 distance therefrom.

7. In a piano, a vibratable element operated by the keyboard of the piano, a loud speaker, sound amplifying devices, means for placing said vibratable element, said amplifying devices and 50 said loud speaker in sound-transfer relation, and means for adjusting the spacing of said loud speaker with respect to said vibratable element.

8. In a piano, a piano sounding board, a loud speaker, means for impressing electric variations 55 corresponding to sound variations on said loud speaker, and means for adjusting the spacing of the loud speaker as a whole with respect to said sounding board to obtain different tone characteristics. 60

9. In a musical instrument, a sounding board, a plurality of polyphonic strings adapted to be set into vibration and to impart vibrations to the sounding board, electric pick-up means on said sounding board, a loud speaker adjustably associated with said sounding board, and a power and amplifying device for augmenting the power transmitted to said loud speaker, said amplifying device being fed by said pick-up means, and means for adjusting the spacing of said loud speaker 70 with respect to said sounding board. 65
